United States Patent Office.

E. W. TUCKER, OF LOWELL, MICHIGAN.

Letters Patent No. 94,670, dated September 7, 1869.

IMPROVED SPRING FOR UPHOLSTERY, CHAIR, CAR, AND OTHER SEATS.

The Schedule referred to in these Letters Patent and making part of the same.

To all whom it may concern:

Be it known that I, E. W. TUCKER, of Lowell, in the county of Kent, and in the State of Michigan, have invented certain new and useful Improvements in Springs for Upholstery, Chair, and Car-Seats; and do hereby declare that the following is a full, clear, and exact description thereof, reference being had to the accompanying drawings, and to the letters of reference marked thereon.

The nature of my invention consists in the construction of a wire spring, which may be used in any kind of a seat, or for upholstering.

In order to enable others skilled in the art to which my invention appertains to make and use the same, I will now proceed to describe its construction and operation, referring to the annexed drawings, which form a part of this specification, and in which—

Figure 1 is a vertical section of a seat with my improved spring, and

Figure 2 is a perspective of the spring.

A represents the frame of the seat, to which the cushion B is secured. On top of the frame A, along its sides, are placed round bars C C, around which the

ends of the springs D D are placed; said springs extending across the frame under the cushion, the cushion resting on the springs.

The spring D is made of wire, twisted at the ends, so as to form the loops a a, and also turned in the centre, so as to form the ring b, which thus becomes an expanding joint, allowing the spring to be depressed.

In fact, the spring D is the lifting-spring, combined with one or more expanding joints, which latter are necessary to make it a perfect-working spring.

Having thus fully described my invention,

What I claim as new, and desire to secure by Letters Patent, is—

The arrangement, under the fabric B, of the spring D, with end-loops a a, coiled around the circular bars C C, and the intervening loops b, all as herein set forth.

In testimony that I claim the foregoing, I have hereunto set my hand, this 6th day of January, 1869.

E. W. TUCKER.
